UNITED STATES PATENT OFFICE.

DANIEL O. ASPELUND, OF BROOKLYN, NEW YORK.

STEAM-REGULATING DEVICE.

1,247,611.

Specification of Letters Patent. Patented Nov. 27, 1917.

Application filed May 22, 1917. Serial No. 170,232.

To all whom it may concern:

Be it known that I, DANIEL O. ASPELUND, a citizen of Norway, and resident of Brooklyn, in the county of Kings and State of New York, have invented certain new and useful Improvements in Steam-Regulating Devices, of which the following is a specification.

This invention relates to regulating devices and has particular reference to a steam regulating device adapted to be used on board vessels for automatically throttling the steam supply when the propeller is raised out of the water by the motion of the vessel in the sea, so as to prevent the engine from racing, and for automatically opening up for the steam supply when the propeller is again submerged. With these and other objects in view, my invention is embodied in a regulating device arranged and constructed as hereinafter set forth and as illustrated in the accompanying drawing in which

Figure 1 is a diagrammatic view of a vessel equipped with my improved regulating device, and

Fig. 2 is a detail view of the regulating device.

Referring to Fig. 2 the regulator is shown as comprising a cylinder 3 in which moves a piston 4 having a piston rod 5. A spring 6 or other device tends to keep the piston near the right hand end of the cylinder. To the latter is connected a pipe 7 having a valve 8. The pipe extends through the side 35 of the vessel 9 to the outside thereof, where a flexible pipe 10 is connected to the pipe 7 by a coupling 11.

Referring to Fig. 1 it will be seen that the regulator is mounted with the pipe 10 near the propeller 12 of the vessel. The piston rod 5 is connected to and operates a pole changing mechanism 14 which is connected to a powerful magnet or solenoid 15, and a source of electric current 16. The solenoid 45 through its core 17 operates a throttle valve 18 in the steam supply pipe 19 leading from the boiler 20 to the engine 21.

So long as the propeller and the pipe 10 are in the water, the rearward suction in the pipes 10 and 7 created by the ship passing through the water, causes a vacuum within the cylinder 3 to the left of the piston 4 and the latter will be drawn into the posi-

tion shown in Fig. 1 and the current through the solenoid 15 will operate the core 17 to open the valve 18 to supply sufficient steam to the engine. The cylinder is provided with air openings 24 so that the air pressure on the piston on the one side thereof will assist in moving said piston toward the left in Fig. 2, and as illustrated in Fig. 1.

When, however, the movement of the vessel raises the propeller out of the water, which movement of course also raises the pipe 10, the suction in said pipes 10 and 7 ceases and the spring 6 operates the piston and piston rod 5 to actuate the pole changer so as to reverse the current in the solenoid 15 which will then operate to close the valve 18 and thus throttle the steam supply to the engine and prevent the same from racing. When the propeller and the pipe 10 are again submerged the former or normal condition will again exist and the valve 18 will be opened wide. The movement in opposite directions by the core 17 may be accomplished in any well known manner as for instance by polarizing said core, which is an old expedient for securing reversal of movement of the core corresponding to reversal of direction of current in the solenoid.

The valve 8 is for the purpose of cutting the cylinder off from the suction pipes in case of leaks, repairs and the like. The pipe 7 is shown straight in Fig. 1 and curved in Fig. 2 to illustrate that the particular arrangement thereof may be made to suit local requirements.

It will further be observed that my invention is not limited for use with steam power plants but is applicable to engines using other fuel. The pipe 10 is preferably flexible so as to follow the movements of the vessel in the water to avoid breaking the same.

I claim:

The combination with a vessel, its steam engine and boiler and a valve for controlling the steam supply from the said boiler to the said engine, of a regulating device mounted adjacent the propeller of said vessel and comprising a cylinder, a pipe of smaller diameter than said cylinder leading from the latter to the outside of said vessel below the water line, a flexible pipe connect-

ed to the said pipe outside of the vessel, a piston in said cylinder adapted to move in response to the suction created at the stern of the vessel when the latter is in motion and its propeller submerged, means for operating said piston in the opposite direction when the propeller is not submerged and

mechanism controlled by the said piston for regulating the said controlling steam supply valve.

10

Signed at New York, in the county of New York and State of New York, this 19th day of May, A. D. 1917.

DANIEL O. ASPELUND.
